(57) **CLAIM**

The ornamental design for a dispenser for earplugs, as shown and described.

DESCRIPTION

FIG. 1 is a front perspective view of a dispenser for earplugs, according to my design;

FIG. 2 is a front elevational view thereof;

FIG. 3 is a left side elevational view thereof and with the other side being a mirror image;

FIG. 4 is a back elevational view thereof;

FIG. 5 is a top plan view thereof; and,

FIG. 6 is a bottom plan view thereof.

In FIGS. 2, 3, 4 and 6, the broken lines are for the purpose of illustrating portions of the dispenser for earplugs that form no part of the claimed design.
